GRINDING MACHINE

Wilhelm Beer, Wiesbaden-Dotzheim, Germany

Application March 20, 1951, Serial No. 216,545
In Germany April 3, 1950

7 Claims. (Cl. 51—28)

1

This invention relates to a grinding machine. In particular, the invention is directed to a machine for grinding valves, plugs, plug cocks, stoppers, etc., into their seats.

In the manual grinding of valves, plugs, or stoppers, into their seats, a very desirable grinding procedure is inherently present. For example, the valve, after being coated with grinding paste, is turned upon the seat, first in one direction, and then in the other, the valve being lifted between various rotations and the grinding paste replenished. The degree of turning, or the number of revolutions during the turning in one direction, is irregular so that a kind of a step by step overlapping process prevents overground surface areas, such as would occur if the turning were always started and stopped at the same point. Furthermore, the hand operation permits the valve to center itself with respect to the valve seat, the hand manipulated turning instrument yielding to any inclinations necessary for centering.

In the known mechanical valve grinding machines, the desirable technique of hand grinding has not heretofore been achieved. In one type of machine the valve is periodically lifted from the seat so that the grinding paste can be replenished, but the rotation of the valve is always in the same direction. This permits any errors of adjustment between the seat and the valve to become accentuated during the grinding. In another form of machine, the valve is rotated first in one direction and then in the other by a system of gears and levers, but the valve constantly engages the seat. Therefore, the grinding paste cannot be replenished, and any foreign object which may have gotten into the paste in the beginning will produce objectionable scores in the valve seat.

The objects of the instant invention are to produce a machine which very closely simulates the hand grinding of valves, plugs, or stoppers, into their seats; to produce a machine in which the valve being ground is periodically lifted from its seat, but is not re-seated at the same point; to produce a machine in which a reversal of direction of grinding takes place as the valve is lifted from its seat; to produce a machine to obtain a step by step progressive overlapping grinding process; and to produce a self-centering table for holding the workpiece containing the valve seat.

In general, these objects of the invention are obtained driving a spindle in alternate directions by a pair of friction disks. A sleeve telescopically engages the spindle and is splined thereto, the

2

lower edge of the sleeve carrying a chuck for holding the valve. A cam system causes the friction disks to turn the spindle successively in alternate directions, and to lift the sleeve at the moment the spindle is being changed in its direction of rotation. This cam system also holds the valve free of the seat for a longer time in one direction of spindle rotation than the other, so that when grinding is resumed successively, a progressive step by step overlapping grinding occurs. The workpiece containing the valve seat is held on a table which is self-adjusting in any horizontal direction, and self-inclining to any angle from the vertical, so that the valve seat automatically centers itself with respect to the valve.

The means by which the objects of the invention are obtained are more fully described with reference to the accompanying drawings, in which:

Fig. 1 is a side elevational view, partly in section, of the machine;

Fig. 2 is a longitudinal cross-sectional view through the grinding spindle and chuck carrying sleeve;

Fig. 3 is an enlarged detailed view of a portion of a driving disk;

Fig. 4 is a front view, partially in section, of the supporting table;

Fig. 5 is a side view, partially in section, of Fig. 4; and

Fig. 6 is a schematic representation of the grinding process produced by the machine.

In Fig. 1, a base 2 supports a frame 4, housing motor M which is connected by belt 6 to sheave 8, driving a worm gear 10. This worm gear in turn drives gear 12 secured to shaft 14, which is journaled at each end in the upper portion 16 of frame 4. Slidably mounted on and splined to shaft 14 are two friction disks 18 and 20, respectively. These disks are urged toward the center of the shaft by springs 22 and 24, respectively. Intermediate the disks 18 and 20 is a cam 26 splined to shaft 14 and slidable thereon by means of a stationary pin 28, which is fixedly held to housing portion 16 by means of a bracket 30. A cam 32 is also fixed to shaft 14 for a purpose later to be described.

A vertical spindle 33 is journaled in a bracket 34 appropriately secured to housing portion 16, the bearing including conventional thrust bearings (not shown) against vertical displacement. The upper end of spindle 33 carries a friction disk 36, while the lower end of spindle 33 extends downwardly into bearing 38 mounted in housing portion 16. A sleeve 40 is telescoped

over the spindle 3 and is splined thereto, the sleeve extending through bearing 38. The lower end of this sleeve carries a chuck 42 which holds the valve, plug, or stopper 44.

A nut 46, which includes an annular collar, is 5 threaded on sleeve 40. A compression spring 48 extends between this nut 46 and a collar 50, which abuts bearing 34.

A rod 52 held by brackets 54 to housing portion 16, extends between cam 32 and a lever 56, which is pivoted at 58, and the other end of which engages nut 46. An adjustable spring 60 is attached to one end of lever 56 in order to vary the tension thereon.

In Fig. 3 a portion of friction disk 20 is illustrated, a similar construction existing for disk 18. These disks are composed of cast iron with copper plugs or rivets 62 inserted therein in order to increase the frictional qualities of the surfaces of the disks. The periphery of the disk is provided with a groove 64. One face of the disk has a greater diameter than the opposite face, thus producing a flange 66. Consequently, any oil which may accumulate on either face of the disk is by centrifugal force first collected in groove 64, and then flows to the edge of flange 66, from which it is flung from the disk.

The operation of this portion of the machine is as follows:

Shaft 14 upon being rotated by motor M causes cam 26 to move either to the right, or to the left, in accordance with the position of the groove in the cam follower with respect to fixed pin 28. As the cam moves to the right, it will engage disk 20 and push it against the pressure of spring 24 out of engagement with disk 36. At the same time, disk 18 will move under the pressure of spring 22 into engagement with disk 36, and will rotate the disk connected to the spindle 33 and sleeve 40. This rotation continues until cam 26 is again shifted, so that disk 18 becomes disengaged and disk 20 re-engages disk 36 to rotate the spindle in the opposite direction.

At the moment either of the disks becomes disengaged from disk 36, cam 32 comes into operation to push down rod 52 and thereby actuate lever 56 to raise sleeve 40 against the pressure of spring 48. This, of course, will raise the valve or plug 44 out of engagement with the valve seat and permit the grinding paste to be replenished.

Cam 32 is formed to hold sleeve 40 elevated while re-engaged by either of the driving friction disks, 18, 20, for a longer period of time than the other. The result of this is that when the sleeve is lowered to resume grinding, the valve in grinding engagement is always turned in one direction a greater number of revolutions than it is turned in the opposite direction, thus causing a progressive grinding in the direction of the greater number of revolutions. In Fig. 6 such is schematically illustrated where *a* represents the beginning of the grinding in, say, a clockwise direction, for a period of time represented by the solid line. At the point *b*, the first driving disk has been disengaged from the spindle 34, and the second driving disk meets disk 36, and spindle 34 begins to revolve in the opposite direction, dash line *c*, but does not set the valve in the seat until sleeve 40 has been permitted to lower at *d* by reason of cam 32. By the time the sleeve has lowered, the grinding 70 extends only over a period of time equal to the

length of the solid line *e*, following which at *f* the sleeve is again lifted and the valve is disengaged from the seat during the length of time represented by the dash line *g*, plus the sleeve lowering time *h*, and grinding again starts as represented by the solid line *i*. This grinding is thus repeated until the valve is ground in, it being noted that the point of re-engagement of the valve with its seat always varies progressively in one direction, with a step by step overlapping process.

The length of grinding for any series of objects can be determined experimentally, and then a time switch S, attached to motor M, set for the grinding of an object; the machine stopping itself when the grinding is completed. The pressure of the valve on the seat can be adjusted by varying the tension on spring 60.

The supporting table is constructed so as to adjust itself to center the workpiece containing the valve seat, with respect to the valve. In general, the base 70 is vertically adjustable on tracks 72 secured to frame 4, this base being vertically movable by means of a lift 74. Carried on the base is the table 76, shown in detail in Figs. 4 and 5, and upon which is mounted the workpiece 77 containing the valve seat.

Mount 76 consists of a base plate 78 containing longitudinal grooves 80, anti-friction balls 82 moving in these grooves and supporting plate 84 for movement in the direction of grooves 80. The upper surface of plate 84 contains a centrally extending groove 85 running at right angles to grooves 80.

30 A plate 86 rests on plate 84, plate 86 having a projection 88 engaging groove 84a. Plate 86 is therefore movable at right angles to plate 84, this movement being facilitated by anti-friction balls 90 contained in grooves 92 in the bottom surface of plate 86, said grooves 92 being parallel to groove 84a. Plates 84 and 86 are held on base plate 78 by means of flange 85 secured to plate 78 and surrounding plates 84 and 86. An inturned flange 85a extending along two parallel sides of plate 86 holds the plates against vertical separation.

40 A plate 94 carrying jaws 96 is mounted on plate 86 by means of a ball and socket 98. It is noted that the upper surface 87 of plate 86 is slightly conical in shape with the locus of the apex at the ball and socket joint, which permits the spherical ball to be held in place upon plate 86 by means of holding plates 100 screwed to plate 86, access to the heads of the screws being obtained by holes 102 in plate 94. Plate 94 thus is slightly tiltable from the vertical in any angular direction, a normally horizontal position being maintained by soft springs 104. The jaws 96 are actuated by the conventional shaft 106 turnable by wheel 108.

50 When a workpiece containing the valve seat is placed between jaws 96 and brought to a position between the valve 44, the mount 70 is raised to bring the seat into contact with valve 44. Plates 84 and 86 will adjust themselves to center the valve seat with respect to the valve, while plate 94 is slightly tiltable on socket 98 in order to compensate for any inclination of the valve with respect to the valve seat. A substantially perfect centering is thus assured, and grinding can begin without further adjustment.

60 The machine described substantially reproduces the technique of hand grinding and all of the advantages therewith. The seating of the 70 valve seat and the valve in the machine is ac-

complished quickly and without the time necessary to obtain accurate centerings, as in former machines. The pieces having been set in place, the motor is started and the operation of grinding continued without further attention, except for the replenishment of the grinding paste, until the valve has been ground in.

While for purposes of convenience the machine has been, for the most part, described with reference to grinding in of a valve, it is clear that the machine is useful for grinding in many other objects, such as stop cocks, bottle stoppers, plug cocks, and plugs of various sorts.

Having now described the means by which the objects of the invention are obtained, I claim:

1. In a machine of the type described, means for grinding a valve-like plug into a seat comprising a flat base plate, a work piece holder for a valve seat supported on and fixed to said base plate against rotation and being free for parallel movement in all directions with respect to said base plate, means for holding a valve-like plug into grinding engagement with the valve seat, means for rotating said holding means intermittently in successively opposite directions, and means for disengaging said holding means and the plug from the valve seat while reversing the direction of rotation of said holding means, said work piece holder being centered by the plug held by said plug holding means.

2. In a machine as in claim 1, said rotating means comprising a drive shaft, a pair of spaced disks mounted upon said shaft, a spindle connected to said holding means, and means for alternately clutching each disk of said pair with said spindle.

3. In a machine as in claim 2, said clutching means further comprising a pair of springs for urging each of said pair of disks into contact with said spindle, and cam means for moving said disks against said springs.

4. In a machine as in claim 3, each disk having one face of larger diameter than the opposite face forming a circumferential flange, and an oil collecting groove at the base of said flange.

5. In a machine as in claim 4, each disk being composed of cast iron, and friction increasing copper inserts in the spindle contacting face of each disk.

10 6. In a machine as in claim 1, said work piece holder comprising, a pair of superimposed plates mounted upon said base plate for relative movement parallel to said base plate and cross-wise with respect to each other, and a workpiece gripping plate vertically inclinably mounted upon said pair of plates.

20 7. A self-centering workpiece support comprising a base plate, a first plate, means mounting said base plate for linear movement upon said base plate, a second plate, means mounting said second plate upon said first plate with movement perpendicular to the movement of said first plate upon said base plate, a workpiece gripping plate, and universal movement 25 means for mounting said gripping plate upon said second plate.
